UNITED STATES PATENT OFFICE.

LEO DE REAMER, OF NEW YORK, N. Y.

DESIGN FOR A MATCH-SAFE.

47,774.

Specification for Design. Patented Aug. 31, 1915.

Application filed July 9, 1914. Serial No. 850,020. Term of patent 3½ years.

To all whom it may concern:

Be it known that I, LEO DE REAMER, a citizen of the United States, residing in the borough of Brooklyn, county of Kings, city and State of New York, have invented a new, original, and ornamental Design for a Match-Safe, of which the following is a specification, reference being had to the accompanying drawing, forming a part thereof.

The figure is a perspective view of a match safe showing my design.

I claim:

The ornamental design for a match safe substantially as shown.

In witness whereof, I have hereunto set my hand at the city, county and State of New York, this 2nd day of June, 1914.

LEO DE REAMER.

In presence of—

A. M. HAYES,
